PHOTOSENSITIVE SWITCH CONTAINER

David A. Selick, 196 Riveredge Road, Tenafly, N.J.

Filed Feb. 14, 1962, Ser. No. 68,811

Term of patent 14 years

(Cl. D26—1)

FIG. 1 is a front elevational view of a photosensitive switch container embodying my new design;

FIG. 2 is a side elevational view thereof;

FIG. 3 is a rear elevational view thereof;

FIG. 4 is a top plan view thereof; and

FIG. 5 is a bottom plan view thereof.

I claim:

The ornamental design for a photosensitive switch container, as shown.
